UNITED STATES PATENT OFFICE.

LE GRAND PARISH, OF NEW YORK, N. Y.

LOCOMOTIVE-FIRE-BOX CONSTRUCTION.

1,110,815.

Specification of Letters Patent. Patented Sept. 15, 1914.

Application filed June 15, 1914. Serial No. 845,078.

To all whom it may concern:

Be it known that I, LE GRAND PARISH, a citizen of the United States, residing in the borough of Manhattan, in the county, city, and State of New York, have invented certain new and useful Improvements in Locomotive-Fire-Box Construction, of which the following is a specification.

My invention relates to an improved arrangement of circulating arch tubes in a locomotive fire-box whereby increased and more constant circulation of the water between the different parts of the fire-box is obtained, while at the same time the tubes are so arranged that it is possible to support the individual bricks constituting the refractory arch accessibly and removably on any of the tubes. In connection with the foregoing, my invention contemplates the protection and the prolongation of the life of the refractory arch by virtue of the improved arrangement of the tubes whereby the bricks are subjected to the beneficial cooling action of the tubes; and the arrangement of the tubes of the fire-box in such manner that greater efficiency with respect to the quantity of fuel consumed, and better and more complete combustion of the gases, is obtained. In general, my invention contemplates the provision of an improved arrangement of the tubes whereby characteristics and advantages described, which can be readily installed in standard locomotive constructions, and presents no obstruction in assembling, removal, replacement, repair, or inspection of the various component parts of the fire-box.

The foregoing objects, as well as such as may hereinafter appear, or are incident to my invention, I attain by means of a construction which I have illustrated in preferred form in the accompanying drawings, wherein—

Figure 1 is a longitudinal section through the fire-box of a locomotive illustrating my invention applied thereto; Fig. 2 is a section through the device of Fig. 1 taken on the line II—II of said figure; and Fig. 3 is a transverse section similar to that of Fig. 2 but illustrating an arrangement whereby the refractory arch is supported on tubes extending in different planes.

Referring now to the drawings, it will be seen that the fire-box illustrated is of the standard type for locomotives and is

composed of an inside fire-box comprising a tube sheet 1, side sheets 2, a back sheet 3, and a crown sheet 4; an outside fire-box comprising the throat sheet 1^a, side sheets 2^a, a back sheet 3^a, and a top or cover sheet 4^a. The water spaces at the front, sides, and rear of the fire-box are closed by a mud ring 5. The sheets on opposite sides of the water spaces are secured or connected together by the stay bolts 6, while the crown sheet and cover sheet are connected by radial stay bolts 7. At the front of the inner fire-box, the tube sheet 1 is carried up to provide the usual flue sheet 18 into which the ends of the flues 12 are fastened. The parts thus far described are of the usual construction.

Attention is now directed to the circulation and arch tubes. It will be seen that I have arranged two rows of circulation tubes 8 and 8^a, which extend rearwardly and upwardly from the tube sheet 1 to the back sheet 8, and connect the front and rear water spaces of the fire-box. Each row is preferably composed of four tubes, the tubes of one row lying above the tubes in the other in order to permit of the placing of the arch bricks 9 in proper position, and also to afford sufficient space to permit of workmen getting between the tubes to make repairs to the flue sheet or flues. This arrangement also does not interfere with the inspection or repair of the stay-bolts, which is of importance. Access is had to the interior of the tubes by means of the wash-out plugs 10 and 11, respectively located in the back sheet 8^a and throat sheet 1^a.

I have found by experience that this construction increases, and in fact practically doubles the circulation between the water walls of the fire-box, which of course results in added efficiency to the fire-box without increasing the quantity of fuel consumed.

In addition to the advantages herein set forth, either of the rows of circulation tubes may serve as a means for supporting the brick arch of the fire-box, or they may be supported on some tubes of both rows as shown in Fig. 3. As shown in Figs. 1 and 2, the arch is supported on the lower row 8 of the tubes, a particular advantage residing in this arrangement because the combustion of the gases in the fire-box is not retarded, but assisted. It has been found that complete combustion of the gases in the fire-box is

delayed where the gases come in contact with the relatively cool surfaces of the circulating tubes, and it will be clear that in a construction such as that described, there will be considerable cooling action because of the larger number of tubes. By supporting the arch on the lower tubes, the gases do not come directly in contact with the upper tubes and combustion is not delayed, while at the same time the advantages of increased circulation and general efficiency are obtained. In the construction shown in Fig. 3, the arch bricks are supported on both rows of tubes, extending transversely across the fire-box, and presenting an irregular profile in cross section. By this arrangement, the arch provides mixing channels or spaces which modify the direction of the flow of the products of combustion, and secure an intimate admixture of the gases which results in more perfect and complete combustion.

An additional advantage is obtained by the foregoing constructions with respect to the arch 9, inasmuch as it will be clear that the upper surfaces of the bricks are to some extent protected by the circulation tubes through which there is a flow of relatively cool water from the fire-box walls absorbing a portion of the heat passing over the arch. This prolongs the life of the bricks.

It will thus be seen that the individual bricks constituting the refractory arch can be removably and accessibly supported on any of the tubes, and that free access is had not only in assembling, but also in removal, repair, replacement, or inspection. The utility of the arrangement herein described is further shown in the developments illustrated and described in my co-pending applications Serial Nos. 838,652, 838,653, and 838,654, filed May 16, 1914, which contain subject matter not herein specifically claimed.

I claim:

1. A locomotive fire-box comprising in combination with water spaces, a plurality of circulating tubes extending rearwardly and upwardly from one water space to another and arranged in two rows, spaced one substantially above the other, with the tubes in substantial parallelism whereby an arch brick wall supported on any of the tubes can be accessibly and removably supported thereby.

2. A locomotive fire-box comprising in combination with water spaces, a plurality of circulating tubes extending rearwardly and upwardly from one water space to another and arranged in two rows, one above the other, and an arch wall supported on the tubes of the lower row and extending rearwardly from a point adjacent the forward end of the tubes a portion of the distance to the rear water space, the said wall protecting the tubes of the upper row from direct contact with the intense heat but subjecting said tubes to the action of the hot gases passing from the rear of the wall forwardly above the wall.

3. A locomotive fire-box comprising in combination with water spaces, a plurality of circulating tubes extending rearwardly and upwardly from one water space to another and arranged in two rows, spaced one above the other with the tubes in substantial parallelism and one located above the other whereby an arch brick wall can be accessibly and removably supported on one of the rows of tubes.

In testimony whereof I have hereunto signed my name in the presence of the two subscribed witnesses.

LE GRAND PARISH.

H. B. SLAYBAUGH.

Copies of this patent may be obtained for five cents each, by addressing the "Commissioner of Patents,
Washington, D. C."

It is hereby certified that in Letters Patent No. 1,110,815, granted September 15, 1914, upon the application of LeGrand Parish, of New York, N. Y., for an improvement in "Locomotive-Fire-Box Construction," an error appears in the printed specification requiring correction as follows: Page 1, line 31, for the words "of the tubes whereby" read *having the character*; and that the said Letters Patent should be read with this correction therein that the same may conform to the record of the case in the Patent Office.

Signed and sealed this 6th day of October, A. D., 1914.

[SEAL.]

R. F. WHITEHEAD,

Acting Commissioner of Patents.
